CLAIM

The ornamental design for a balaclava, as shown and described.

DESCRIPTION

FIG. 1 is a front elevational view of a balaclava showing my new design;

FIG. 2 is a rear elevational view of FIG. 1;

FIG. 3 is a right side view of FIG. 1;

FIG. 4 is a perspective view of FIG. 1;

FIG. 5 is a front elevational view showing the balaclava in a first use state;

FIG. 6 is a rear elevational view of FIG. 5;

FIG. 7 is a right side view of FIG. 5;

FIG. 8 is a perspective view of FIG. 5;

FIG. 9 is a front elevational view showing the balaclava in a second use state;

FIG. 10 is a rear elevational view of FIG. 9;

FIG. 11 is a right side view of FIG. 9;

FIG. 12 is a perspective view of FIG. 9;

FIG. 13 is a perspective view showing the balaclava in a third use state;

FIG. 14 is a perspective view showing the balaclava in a fourth use state; and,

FIG. 15 is a perspective view showing the balaclava in a fifth use state.

The broken lines in FIGS. 10-11 and 13-15 depict a partial human figure showing how the claimed design may appear when in use and forms no part of the claimed design.

1 Claim, 15 Drawing Sheets
